UNITED STATES PATENT OFFICE.

LOUIS P. VALIQUET, OF CHICAGO, ILLINOIS.

DRIVING MECHANISM FOR PHONOGRAHS.

Application filed September 4, 1923. Serial No. 680,711.

To all whom it may concern:

Be it known that I, LOUIS P. VALIQUET, a citizen of the United States, and a resident of Chicago, in the county of Cook and State of Illinois, have invented certain new and useful Improvements in Driving Mechanism for Phonographs, of which the following is a full, clear, and exact description.

The present invention relates to motor-operated driving mechanism for talking machines and its primary object is to provide improved driving mechanism by which the talking machine record will be driven at a uniform speed despite variations in the speed of the motor, resulting from fluctuations in the current supplied to the motor.

The invention consists in the several novel features hereinafter set forth and more particularly defined by claims at the conclusion hereof.

In the drawings: Fig. 1 is an inverted plan of mechanism embodying the invention. Fig. 2 is a diagram of the electrical connections. Fig. 3 is a side elevation, parts being shown in section. Fig. 4 is a section taken on line 4—4 of Fig. 3. Fig. 5 is a longitudinal section of the governor for cutting one resistance coil into and out of the motor circuit. Fig. 6 is a section on line 6—6 of Fig. 5. Fig. 7 is a vertical axial section through the slip joint through which the turn-table shaft 11 is driven. Fig. 8 is a section on line 8—8 of Fig. 5.

In the exemplification of the invention illustrated, the driving mechanism is all mounted on and supported by a frame or bed-plate 9. The record turn-table 10 is mounted on and rotated by a vertical shaft 11 which is driven by power derived from an electric motor 12 which is suitably secured to the underside of frame 9. The armature shaft 13 of motor 12 carries a fly-wheel 14 and drives a shaft 15 through a flexible coupling 16 of well-known construction. Shaft 15 is supported in bearings 18 of a housing 17 which depends from and is fixed to the underside of frame 9. An adjustable screw 19 forms a thrust bearing for the vertical shaft 11. A worm 20, cut in shaft 15, meshes with a worm-wheel 21 which is loose on shaft 11 and forms one member of a slip joint through which shaft 11 is driven. Gear 21 is mounted between and engages with two fibre friction disks 22 and 23 which are also loose on shaft 11. A metal disk 24 engages fibre disk 22 and a disk 25 integral with shaft 11

engages fibre disk 23. A pin 26, rigid with shaft 11, has its ends projecting into notches in disk 24 to rotate the disk with the shaft and permits slight relative axial movement between the disk and the shaft. A plate 27 is provided with spring-fingers 28, which bear upon disk 24 to maintain the required friction or pressure between the members of the slip joint. A nut 29 threaded to shaft 11 may be adjusted to regulate the pressure of fingers 28 against disk 24 to correspondingly regulate the friction between the members of the slip joint. A plate 30 is held in housing 17 by a screw 31 and forms the top of the chamber containing the slip joint so that a lubricant of suitable viscosity will be retained in said chamber. An oblique toothed gear 32 is fixed to shaft 11 and meshes with a worm 33 cut on a shaft 34 to operate a speed or governor controlled braking device. Shaft 34 is supported in bearings 35 mounted in lugs 36 which depend from the frame 9.

This governor comprises a disk 37 slidable on shaft 34, a collar 38 fixed on said shaft, leaf-springs 39 connecting collars 38 and the hub of disk 37, and weights 40 attached to the springs. A friction pad 41, mounted on an arm 42, cooperates with said disk to control its speed so that when the speed of shaft 34 becomes excessive, disk 37 will contact with pad 41 to act as a drag on the shaft 11. Arm 42 is pivoted, as at 43, to frame 9 and at its opposite end is provided with a slot 44 into which projects a pin 45 depending from a shaft 46 which extends through and is journaled in frame 9 and to the upper end of which is secured an adjusting handle 47. By adjusting the handle to shift the brake-pad 41 to or from the governor disk 37, the relation between the disk 37 and brake-pad 41 may be varied to render them operative to maintain different predetermined speeds of the shaft 11.

In practice, it has been found that a governor brake does not, under all conditions, result in the accurately uniform speed desired of the turn table and record, as the result of substantial fluctuations in the voltage of the current supplied to the motor 12, and one of the primary objects of the present invention is to provide for more accurate maintenance of the governed speed of the disk record than has heretofore been possible in constructions whereof I am aware. In practice, the variations in

a normal 110 volt supply circuit are known to vary, sometimes dropping to as low as 75 or 80 volts when the peak load is placed on the generating system and at other times, 5 under a minimum load, the voltage increases somewhat above the normal. To compensate for these variations, the motor 12 is wound to maintain the maximum speed desired for the turn-table at a voltage lower 10 than the minimum in the supply circuit and a resistance coil 50 is included in the normal circuit to the motor. The supply circuit is exemplified in Fig. 2 by a conductor 51 connected to one end of coil 50, a conductor 52 between the other end of said coil and a binding post 53, a switch comprising a contact 58 connected to said post and a contact 59 connected to a binding post 60, a conductor 54 between the post 20 60 and the motor and a leading-in conductor 55. A second resistance coil 56 is included in a conductor 57 between the motor and a binding post 53. The switch 58, 59 is governor-controlled and is normally closed to 25 furnish a direct path between coil 50 and motor 12 through its contacts, and when open, interrupts said path, so that the circuit will include conductor 57 and resistance coil 56.

30 A governor for said switch comprises a hub 61, which is fixed to a shaft 15, a pair of arms 62, 63 pivoted in said hub at 64 and 65 respectively, weights 66 secured to said arms respectively, and a stud-shaft 67 35 slidably mounted in shaft 15 and provided with an abutment 68 adapted to be shifted outwardly by surfaces 69 on arms 62 and 63, to operate switch-contact 59 against the force of a coil spring 68' which is held to 40 act on abutment 68 by a governor housing 73.

Coils 50 and 56 are suitably secured to the under side of frame 9. Coil 50 is of sufficient resistance to reduce the maximum voltage of a 110 volt line to about 80 volts. 45 Coil 56 is of sufficient resistance to further reduce the voltage when that becomes necessary to maintain the desired predetermined speed. Binding posts 53 and 60 and switch contacts 58 and 59 are suitably secured to 50 a block 70 of insulation which is fixed to the frame 9. A switch 71 of any suitable construction is provided to control the starting and stopping of the motor.

In operation, the closing of switch 71 55 will establish a circuit including conductor 51, resistance coil 50, conductor 52, post 53, normally closed switch contacts 58, 59, post 60, conductor 54, motor 12, and conductor 55. This circuit is retained until the 60 motor has acquired its desired speed, and the motor will drive the table through the slip connection and under control of governor-controlled braking device 37, 41. During this operation, the resistance coil 65 50 reduces the voltage of the current pass-

ing through the motor 12 to avoid excessive speed. The motor will rapidly pick up its speed while resistance 56 is cut out, but thereafter and as soon as the motor has acquired its predetermined speed, the governor on shaft 15 will operate stud 67 to separate contacts 59, 58, thus opening the circuit therethrough and including in the motor circuit the additional resistance coil 56 and conductor 57, to cause the motor to operate approximately at its normal speed. As a result, provision is made for substantially equalizing the speed of the motor as well as providing the slip connection and braking device for producing uniformity in the speed of the record-carrying table driven through said connection.

In practice, it has been found that resistances in the circuit are insufficient to produce smooth-running driving mechanism and that brakes alone are not efficient for that purpose, and that by combining the resistance control for the voltage of the circuit and a brake for the elements driven through a slip-connection great uniformity in speed of the turn-table can be attained.

The invention exemplifies motor-driven mechanism for driving a phonograph in which the record is driven through a slip-connection with resistance means for causing uniformity in the speed of the motor, and the drive member of the connection and with braking means for causing uniformity in the speed of the table driven through the slip-connection. As a result of combining these instrumentalities in the driving mechanism, irregularities in the operation of the record are effectively avoided.

The invention is not to be understood as restricted to the details set forth, but may be modified within the scope of the appended claims, without departing from the scope of the invention.

I claim:

1. In driving mechanism for talking machines, the combination of an electric motor, a record turn-table, a slip-connection connected to drive said turn-table, gearing between the motor and the slip connection, an electric circuit for said motor, a resistance connected to said circuit, speed-controlled means for automatically cutting the resistance into and out of the circuit and speed-controlled means applied between the slip connection and the turn-table for regulating the speed at which the turn-table is driven through the slip connection.
2. In driving mechanism for talking machines, the combination of an electric motor, a record turn-table, a slip-connection connected to drive said turn-table, gearing between the motor and the slip connection, an electric circuit for said motor, a resistance connected to said circuit, speed-controlled means for automatically cutting the resist-

ance into and out of the circuit and speed-controlled brake means applied between the slip connection and the turn-table for regulating the speed at which the turn-table is 5 driven through the slip-connection.

3. In driving mechanism for talking machines, the combination of an electric motor, a record turn-table, a shaft for said table, a slip-connection connected to drive said 10 shaft, gearing between the motor and the slip-connection, an electric circuit for said motor, a resistance connected to said circuit, speed-controlled means for automatically cutting the resistance into and out of the 15 circuit, and speed-controlled means driven by the slip-connection for retarding the turn-table through the slip connection.

4. In driving mechanism for talking machines, the combination of an electric motor, 20 a record turn-table, a shaft for said table, a slip-connection connected to drive said shaft, gearing between the motor and the slip-connection, an electric circuit for said motor, a resistance-coil connected to said 25 circuit, a speed controlled switch operated by the motor for cutting the resistance into and out of the circuit and a brake for retarding the turn-table driven by the driven element of the slip-connection and applied 30 between said connection and the turn-table.

5. In driving mechanism for talking machines, the combination of an electric motor, a record turn-table, a shaft for said table, a slip-connection connected to drive said 35 shaft, gearing between the motor and the slip-connection, an electric circuit for said motor, a resistance-coil connected to said circuit, a speed-controlled switch for cutting the resistance into and out of the circuit, a brake for retarding the turn-table 40 through the slip-connection and a speed-controlled governor driven through the slip-connection for operating the brake.

6. In driving mechanism for talking machines, the combination of an electric motor, 45 a record turn-table, a shaft for said table, a slip-connection connected to drive said shaft, gearing between the motor and the slip-connection, an electric circuit for said motor, a resistance-coil connected to said circuit, a speed-controlled governor driven by the motor, a switch operated by the governor for cutting the resistance into and out of the circuit, a brake for retarding the turn-table 50 through the slip-connection and a speed-controlled governor driven through the slip-connection for operating the brake.

7. In driving mechanism for talking machines, the combination of an electric motor, 55 a record turn-table, a slip-connection connected to drive said turn-table, gearing between the motor and the slip-connection, an electric circuit for said motor, a plurality of resistance coils, one of which is constantly in said circuit, a switch for cutting the other resistance into and out of the circuit, a speed-controlled governor for operating said switch, and a speed-controlled brake 60 retarding the speed of the shaft.

8. In driving mechanism for talking machines, the combination of an electric motor, 65 a record turn-table, a shaft for said table, a slip-connection connected to drive said shaft, gearing between the motor and the slip connection, an electric circuit for said 70 motor, a plurality of resistance coils, one of which is constantly in said circuit, a switch for cutting the other resistance into and out of the circuit, a speed-controlled governor for operating said switch, a brake for retarding the speed of the shaft, and a governor 75 controlled by the speed of the shaft for operating the brake.

Signed at Chicago, Illinois this 7th day of Aug. 1923.

LOUIS P. VALIQUET.
